UNITED STATES PATENT OFFICE

CHARLES A. GRAVES, OF EAST CLEVELAND, OHIO

DESIGN FOR A SIGN

Application filed April 2, 1931. Serial No. 39,351. Term of patent 7 years.

To all whom it may concern:

Be it known that I, CHARLES A. GRAVES, a citizen of the United States, residing in East Cleveland, in the county of Cuyahoga and State of Ohio, have invented a new, original, and ornamental Design for a Sign, of which the following is a specification, reference being had to the accompanying drawing, forming part thereof.

The figure is a perspective of a sign, showing my new design.

I claim:

The ornamental design for a sign, substantially as shown.

Signed by me this 27th day of March, 1931.

CHARLES A. GRAVES.
